Leo di Rebaylio, Culver City, Calif.

Application December 18, 1944, Serial No. 116,992

Term of patent 7 years

(Cl. D74—1)

To all whom it may concern:

Be it known that I, Leo di Rebaylio, a citizen of the United States, residing at Culver City, in the county of Los Angeles and State of California, have invented a new, original, and ornamental Design for a Memorandum Note Pad Unit, of which the following is a specification, reference being had to the accompanying drawing, forming part thereof.

Fig. 1 is a front elevational view of a memorandum note pad unit, showing my new design; and

Fig. 2 is a side elevational view of the same.

I claim:

The ornamental design for a memorandum note pad unit, as shown.

LEO DI REBAYLIO.
